(57) **CLAIM**

The ornamental design for an electrode cover for a plasma processing apparatus, as shown and described.

DESCRIPTION

FIG. 1 is a front, bottom, and right side perspective view of an electrode cover for a plasma processing apparatus according to the design;

FIG. 2 is a rear, bottom, and left side perspective view thereof;

FIG. 3 is a rear, bottom, and right side perspective view thereof;

FIG. 4 is a front view thereof;

FIG. 5 is a left side view thereof;

FIG. 6 is a right side view thereof;

FIG. 7 is a top plan view thereof;

FIG. 8 is a bottom plan view thereof;

FIG. 9 is a rear view thereof;

FIG. 10 is a cross-sectional view taken along line 10-10 of FIG. 4;

FIG. 11 is an enlarged view of the portion shown in box, labeled, "FIG. 11," in FIG. 10;

FIG. 12 is an enlarged front, bottom, and right side perspective view of the cross-sectional view taken along line 10-10 of FIG. 4;

FIG. 13 is an enlarged rear, bottom, and right side perspective view of the cross-sectional view taken along line 10-10 of FIG. 4; and,

FIG. 14 is an enlarged rear, bottom, and left side perspective view of the cross-sectional view taken along line 10-10 of FIG. 4.

(Continued)

The dot-dash line box shown in FIG. 10 defines the enlarged portion view shown in FIG. 11 and forms no part of the claimed design.
